UNITED STATES PATENT OFFICE.

HERMAN W. MAURER, OF CLEVELAND, OHIO.

COLLAPSIBLE WALL.

Application filed August 16, 1921. Serial No. 492,661.

To all whom it may concern:

Be it known that I, HERMAN W. MAURER, a citizen of the United States, residing at Cleveland, in the county of Cuyahoga and 5 State of Ohio, have invented certain new and useful Improvements in Collapsible Walls, of which the following is a specification.

My invention relates to improvements in 10 collapsible walls, and more particularly to that class or type which are particularly designed and adapted for use as division or partition walls in temporarily forming smaller rooms or compartments in building 15 structures.

The primary object of the invention is to provide a generally improved collapsible wall of the class indicated, which will be exceedingly simple in construction, cheap 20 of manufacture, and efficient in use.

A further object is the provision of an improved collapsible wall which may be readily and quickly extended or set up forming an attractive appearing side or 25 partition wall and which may be readily collapsed or folded up to occupy a comparatively small space, or if desired may be readily removed and used at various places as a portable device.

A still further and very important object 30 is the provision of an improved collapsible wall section or unit adapted to be readily mounted for use and to be connected to one or more sections or units whereby walls or 35 partitions of any desired lengths or dimensions may be formed.

A further and important object of the 40 invention is the provision of an improved expandible and collapsible frame section or unit carrying suitable flexible covering walls on the opposite face sides of the frame section, said walls and frame section providing a dead air space between the covering walls to further deaden or insulate such 45 walls with respect to the transmission of sounds therethrough.

A still further and important object of 50 the invention is the provision of improved wall section collapsing or folding mechanism arranged within and concealed by the flexible covering walls of the section, said operating or collapsing mechanism being adapted to operate or collapse the section 55 individually, or if desired, be connected to a series or plurality of wall sections, where-

by the latter may be operated simultaneously.

With the above mentioned, and other ends in view, the invention consists in the novel construction, arrangement, and combination of parts, hereinafter described, illustrated in some of its embodiments in the accompanying drawings, and particularly pointed out in the appended claims.

Referring to the drawings, forming a 60 part of this specification, Figure 1, is a side elevation of collapsible wall sections or units, constructed in accordance with this invention, applied to or set up in a building structure, the near flexible covering wall 65 being removed, and one of the sections or units being collapsed for the purpose of clearer illustration of the parts.

Fig. 2, a cross-sectional view of the overhanging track or guide-way taken on line 70 2-2 of Fig. 1.

Fig. 3, a vertical cross-sectional view taken on line 3-3 of Fig. 1, the front or near flexible covering wall being in place.

Fig. 4, a horizontal cross-sectional view 80 taken on line 4-4 of Fig. 1, the front or near flexible covering wall being in place.

Fig. 5, a side elevation of the frame section in a partially collapsed position, the spaced covering walls, and collapsing cable 85 members being removed for the purpose of clearer illustration of the parts.

Fig. 6, a side elevation of the inner side 90 of one of the flexible covering walls, detached.

Fig. 7, a cross-sectional view, on an enlarged scale, taken on line 7-7 of Fig. 6, and illustrating one of the arcuately arranged cable gathering strips and rings.

Fig. 8, a diagrammatic side elevation of 95 a modified form of a collapsible wall arranged as a screen, supported from the floor and from the side only.

Fig. 9, a similar view of a further modification in use as a curtain or suspended for 100 vertical movement.

Fig. 10, a side elevation of a modification of the form shown in Fig. 1, in which the frame sections are connected together for simultaneous operation from one end instead of being formed separate and coupled together for individual operation as shown in Fig. 1.

Fig. 11, a side elevation of a further modification in which the flexible coverings 110

are detachedly connected to guide loops in separate guide-ways and the lower ends only connected to collapsible members.

Fig. 12, a sectional view taken on line 5 12-12 of Fig. 11.

Fig. 13, an enlarged fragmentary cross sectional view of the guide rail and detachable carriage suspending loops shown in Figs. 11 and 12.

Similar numerals of reference designate 10 like parts throughout all the figures of the drawings.

In carrying out my invention, I provide an improved collapsible wall section or unit 15 adapted to be readily and conveniently mounted for use and to be connected to one or more sections of like form in providing a wall or partition of the desired lengths and dimensions and in accordance with the 20 particular demands and circumstances to be met.

In providing such collapsible wall section or unit, I provide a suitable collapsible frame section, said frame section, preferably 25 comprising relatively rigid and collapsible frame members flexibly connected to each other as hereinafter more fully described.

The frame section or unit is preferably made up of relatively rigid parallelly extending frame members 1, on two of its sides connected by means of relatively movable 30 flexibly connected collapsible frame or end members 2 on the opposite sides or dimensions.

As a means of causing the collapsible end members 2, to fold inwardly toward each other and between the parallelly extending frame members 1, as the latter are moved toward each other in the collapsing or folding 40 operation as hereinafter more fully described, the interposed collapsible members 2, are hingedly connected by means of hinge members 2^a, arranged on the inner sides to permit this movement, said collapsible frame members 2, being preferably divided as at 45 2^b, midway of their ends and connected by means of hinges 2^c.

As a means of providing double wall faces, adapted to permit of this collapsing action 50 through the movements of said frame, covering walls 3, of a suitable flexible material, such as cloth, rubber, flexible composition, or the like are arranged on the opposite face sides of each frame section, the coverings 3, being secured to the edges of the frame members 1 and 2 in any suitable and convenient manner, preferably by means of suitable tacks or securing elements, and tacking or facing strips 3^a, as shown most clearly 55 in Figs. 3 and 4 of the drawings.

The collapsible frame and wall sections 60 may be either mounted singly and independently for individual collapsing and expanding action as shown in Figs. 1 and 11 of the drawings, or arranged in connected

relation for simultaneous collapsing and expanding as shown in Figs. 8, 9 and 10, of the drawings.

In mounting or setting up the improved collapsible wall within the room or building 70 in which it is to be used, one of the frame members 1, is preferably secured to a side wall or upright member 4 of the building or structure and may be secured thereto by means of securing elements or bolts 4^a. 75

As a means of guiding the wall sections in their expanding and contracting movements when set up, the over-hanging wall or ceiling 5 may be provided with a beam or rail 6, provided with a track 6^a and a guide-way 6^b, (see Fig. 2), suitable carriage brackets 6^c being provided and connected to the upper ends of the movable frame members 1.

The carriage or suspending brackets 6^c, are provided with rollers 6^d, adapted to 85 travel on the track 6^a, in a well known and understood manner.

Where the wall sections or units are mounted separately for individual operation, as shown in Fig. 1, of the drawings, 90 the adjacent frame members 1, may be detachably coupled or connected together by means of suitable coupling or fastening members 7, this form of wall offering the advantage of enabling an opening or passage-way being formed at any point by 95 simply collapsing one of the sections and without in any way disturbing the remaining wall sections.

As a means of initially breaking or drawing inwardly the inner hinged ends of the collapsible ends 2, of the frame section, and thereby drawing the frame members 1 toward each other in parallel relation and carrying therewith the flexible covering wall 100 3, a gathering cord or cable 8, is arranged within each end of the frame section and within the adjacent portion of the flexible covering, each of said cables being connected to a fastening or screw-eye 9, of one of 105 the frame members 1, and being passed through a pulley 10, near the inner pivoted ends of the collapsible members, said cable being arranged in converging loop form and passing through gathering eyes 11, on the 110 inner side of the adjacent covering 3, said eyes 11, being preferably arranged on reinforcing strips 12, arranged in arcuate form with respect to the pivoted portions of the hinge members 2^a. Each gathering cable 8, thence passes over a pulley 13, at one side and on the end member 1, thence passes downwardly in the form of a depending loop 8^a, over a pulley 14, thence upwardly in the form of an intermediate 115 loop 8^b, over a pulley in a double floating pulley block 15, (see Fig. 3) and thence down over a second pulley 13^a, after which the cable passes upwardly along the adjacent frame member 1, and over a pulley 120 125 130

16, after which the cable passes over and through the eyes 11, of the arcuate strip 12, above and over a pulley 17, on one of the collapsible ends and thence over to a fastener eye 18, of the second frame member 1. If desired the intermediate portions of the covering wall 3, may be reinforced and held in a relatively fixed position with respect to each other by means of a plurality of vertically arranged reinforcing strips 19, and cross-bars 20.

As a means of positively causing the upper collapsible members 2, of the frame section, to take their closed or expanded position when the frame section is fully expanded, one of the lower collapsible members 2, is provided with a fastening element or eye 21, and a cable 22, is connected to said fastener 21, and passes over a pulley 23, on one of the upper collapsible members 2, and thence passes over and is connected to the end 24^a, of a projecting lever 24, fastened to the second upper collapsible member 2, this lever or bar 24, extending over the pivoted or intermediate hinge portion of the collapsible members 2, so that when the latter are in their broken position, as shown in Fig. 5, a loop 22^a, is formed by the cable passing over the pulley 23, and it will be obvious that when the lower collapsible members 2, assume their straightened position, when the section is expanded, the movement of the cable 22, will positively draw up the bar 24 in parallel relation with the member 22, as shown most clearly in Fig. 1, of the drawings.

It will be understood that the cables 8 are operated simultaneously by means of a pull cable or cord 25, leading to the floating pulley block 15, such pull cord 25, passing over a pulley 26, and out through a suitable opening on a face of the wall, or if desired two of such pull cords may be employed, the other cord passing out through the opposite wall of the collapsible partition.

In the continuous form of collapsible wall as shown in Fig. 10, of the drawings, instead of the gathering cables 8, terminating at each frame member 1, such cables extend through openings in the intermediate frames 1, and over pulleys 27, so that all of the frame units and wall sections will be simultaneously collapsed and folded in an obvious manner.

In the form shown in Figs. 11, 12 and 13 of the drawings, the upper collapsible members 2, are eliminated and the upper ends of the covering wall 3, are independently mounted, through the medium of a plurality of hooks 28, passing through loop-eyes 29^a, of carriage loops 29, the latter being provided with carriage rollers or wheels 29^b, traveling in the tracks or ways formed by the one piece track 30, which track member 30, also forms an enclosed guide-way, formed

of a single length of sheet metal rolled into suitable shape and attached to the under side of the guide rail 31.

In the form shown in Fig. 8, the lower ends of the frame members 1, may be provided with rollers 32, adapted to travel on the floor and support the frame and wall sections.

In the form shown in Fig. 9, the frame and wall sections are suspended from a suitable over-hanging wall for support, for convenient operation in a vertical direction similar to a curtain, and in an obvious manner.

Having thus described some of the embodiments of my invention, without having attempted to set forth all the forms in which it may be made, or all the modes of its use, what I claim and desire to secure by Letters Patent, is—

1. A collapsible wall, comprising a collapsible frame section carrying spaced flexible covering walls, means for connecting and initially breaking opposite portions of said frame section, and cooperating means for drawing the remaining opposite portions of said frame section toward each other and gathering said flexible covering walls thereover.

2. In a collapsible wall, a frame made up of parallelly extending frame members flexibly connected to each other by inwardly foldable collapsible end frame members, flexible covering walls connected to and enclosing the sides of all of said frame members and adapted to be folded with the latter, and means for collapsing said frame members.

3. A collapsible wall, comprising a plurality of collapsible frame sections each carrying spaced flexible covering walls, means for connecting and initially breaking opposite sides of said frame sections, and cable mechanism cooperating with said frame section connecting and breaking means for drawing the remaining sides of said frame sections toward each other and gathering said flexible covering walls thereover at one side.

4. In a collapsible wall, a collapsible section comprising parallel frame members flexibly connected by collapsible end members, spaced flexible coverings connected to the sides of said frame and end members, and cable members within said coverings connected to said frame and collapsible end members whereby the latter may be collapsed and folded inwardly toward each other between said parallel frame members and the latter and said coverings be folded at one side.

5. In a collapsible wall, a collapsible wall section comprising parallelly extending frame members flexibly connected to inwardly collapsible and foldable end members, spaced flexible coverings connected to

the sides of said frame members, and cable members within said coverings connected to said parallel frame and collapsible inwardly foldable end members whereby the latter 5 may be collapsed and folded inwardly between said parallel frame members and the latter and said coverings be positively folded and collected at one side, respectively, by said cable members.

10 6. In a collapsible wall, a collapsible frame of rectangular form including inwardly relatively movable sides, and collapsible end members extending from one side and connected to the opposite side, said 15 collapsible end members being flexibly connected to the ends of said relatively movable sides and hinged intermediate thereof and provided with flexible pull elements whereby said hinged portions are initially drawn toward each other between the ends of said 20 relatively movable sides of said frame.

7. In a collapsible wall, a collapsible frame section including relatively movable sides and oppositely arranged inwardly 25 foldable frame end members, flexible coverings connected to the sides of said frame members and provided with cable guides, and means within said guides connected to said inwardly foldable frame end members 30 whereby said frame and covering members are collapsed and folded, respectively.

8. In a collapsible wall, a collapsible frame section, including relatively movable sides and flexibly connected inwardly foldable collapsible frame end members, flexible coverings connected to the sides of said frame section and provided on their inner sides with cable guides, and cable members within said guides connected to said inwardly foldable collapsible frame end members 40 whereby said frame and covering members are collapsed and folded, respectively.

9. In a collapsible wall, a collapsible frame section embodying parallelly extending side frame members connected by intermediate inwardly foldable members hinged at the ends of said side frame members, and cable members extending from one side frame member and connected to the other, 45 the intermediate portions of the cable members being flexibly connected to the inwardly foldable ends of said inwardly foldable members thru loop members formed therein whereby said inwardly foldable members 50 are initially drawn toward each other and collapsed between said side members in the folding operation.

10. In a collapsible wall, a collapsible section embodying parallelly extending side frame members connected by intermediate inwardly foldable members hinged on said side frame members, and connections extending from one side frame member to

the other, the intermediate portions being flexibly connected to the inwardly foldable ends of said intermediate foldable members whereby said inwardly foldable members are initially drawn toward each other and collapsed between said frame members in the folding operation. 65 70

11. In a collapsible wall, a collapsible frame of rectangular form including inwardly foldable collapsible sections hinged to form the corners of the rectangular frame, and collapsing cable members extending from one side of the frame and connected to the opposite side, said cable members having their intermediate portions looped and flexibly connected to the inner foldable ends of said collapsible members whereby the latter are initially drawn toward each other between the ends of said frame members as the latter are drawn toward each other in the collapsing operation. 75 80

12. In a collapsible wall, a collapsible wall section comprising a frame section made up of side members and intermediate hingedly connected inwardly foldable members, said inwardly foldable members being hinged to form the corners of the frame section and also hinged intermediate such corners, flexible covering walls on the sides of said frame section and provided with arcuately arranged guides with respect to said hinged corners and terminating at the inner hinged portions of said foldable members, and cables within the guide portions of said coverings connected to one of said sides and flexibly connected to the inner hinged portions of said collapsible members whereby the latter are initially drawn inwardly and the sides drawn toward each other to collapse said frame and fold said flexible covering walls thereover. 85 90 95 100

13. In a collapsible wall, a collapsible wall section comprising a rectangular frame made up of side bars and intermediate hingedly connected inwardly foldable bars, said inwardly foldable bars being hinged to form the corners of the frame and also hinged intermediate such corners, flexible covering walls on the sides of said frame provided with arcuately arranged guides, converging toward the inner hinged portions of said inwardly foldable bars and 110 means within said guides of said coverings connected to one of said side bars and flexibly connected to the inner hinged portions of said collapsible bars whereby the latter are initially broke and drawn inwardly with 115 the side bars toward each other in collapsing said frame and folding said flexible covering. 120

In testimony whereof I have affixed my signature.

HERMAN W. MAURER.
